UNITED STATES PATENT OFFICE

FRANK J. GILROY, OF BUFFALO, NEW YORK; CAMILLA H. GILROY EXECUTRIX OF SAID
FRANK J. GILROY, DECEASED

APPARATUS FOR RAILWAY TRAIN OPERATION

Application filed February 26, 1926. Serial No. 90,832.

The railway cars used in the United States and in Canada are provided with high pressure air brakes, and the passenger cars, with few exceptions, are also equipped for heating with steam, also under relatively high pressure. At the ends of both cars and locomotives there are manually operated valves with short extensions having terminal couplings, which extensions are usually fabric reinforced rubber hose, though my invention applies equally to other types, such as those in which the air brake and steam couplings are combined with the car couplings.

Many trainmen and repairmen have been seriously injured as a result of the sudden escape of steam, hot water or air when manually twisting the hose couplings to separate the same, even after first closing the end valves on both sides of the couplings. This method of uncoupling has therefore been abandoned.

In passenger train service it is now customary for the trainmen to close the steam supply line at the locomotive and blow off all of the steam before reaching any point at which locomotives are to be changed, and when stopped at that point also releasing the air in the entire air brake system. This causes the cooling of the cars at the time when it is most needed, and delays the start beyond the time otherwise necessary because this wasted air must be replaced by a fresh supply before the train can be started, and the replacement of the lost steam is a drain upon the reserve supply of the new locomotive.

In freight service it is customary to uncouple the cars and allow the hose to be pulled apart, often without first closing the end valves. This subjects the hose and coupling gaskets to severe strains which often cause such damage as to require repairs before the cars can be used again. If either valve adjacent to the coupling is open when the hose is pulled apart, there follows an emergency application of the brakes on the car with the open valve and all others coupled thereto. Such emergency applications of the brakes cause cumulative damage to the air brake equipment.

My invention provides a method and ap-

paratus for safely quickly and economically uncoupling the air and steam pipes of these cars without taking the pressure off of either the cars or locomotive, and removes the perils of a closed valve.

In the accompanying drawings, which are illustrative:

Fig. 1 shows in elevation a portion of a coupled train pipe in the usual position.

Fig. 2 is a vertical axial section through one form of my valves, the valve being open.

Fig. 3 is a similar view showing the main valve closed.

Fig. 4 is a section on the line 4—4 of Fig. 2, showing my relief valve closed.

Fig. 5 is a vertical axial section of a modified form of my devices.

Fig. 6 is a section similar to Fig. 3, of my modified form.

Fig. 7 is a vertical section of an alternate form of venting screw cap.

Fig. 8 is a top plan view of the plug shown in Figs. 5 and 6.

In these views A, A represent train pipe segments at the ends of adjacent cars, the cars being omitted, B, B are valves connected to said segments, respectively, C, C' the usual coupling members, and D, D the usual flexible hose segments leading from the valves to the coupling members, respectively.

Each valve is of the usual outline and consists of a casing E provided with an upwardly tapered vertical turnplug F turned by means of a lever G. The plug is shown as working in a fixed bushing H into which it is upwardly pressed by a spring I which reacts against a screw cap J. This screw cap J is provided with a downwardly tapered passage J' from the space below the turnplug to the open air.

The turnplug F is provided with a large transverse passage K through which, when the plug is properly turned, air passes freely between the segments A, D, D, A and is further provided with a small passage L which extends from a portion of the peripheral surface of the plug F, substantially midway between the openings for the passage K, downwardly through the plug to the space beneath, which in turn leads to the open air.

through the passage J'. The passages K and L are so located that when the former aligns with the segments A, D, the latter is closed by the walls of the seat, while a 90 degree rotation of the turnplug closes A and at the same time opens a by-pass from D through the passages L and J' to the outer air.

The tapering of the passage J' permits the escaping fluid to more readily expel any water, dirt or other obstruction.

If the companion turnplug is closed simultaneously with the first, the pressure remains unchanged in A, A so that the relatively small quantity of the fluid trapped in the flexible hose D, C, C' D will escape automatically, without further acts of the trainman, who might forget to operate a separate valve with danger to himself. He is not likely to attempt to disconnect the hose so long as the air or steam escaping through the passage J' warns him that it is dangerous to do so.

If, however, only a single one of my valves is closed, the fluid will continue to escape, and if it is in the air brake system will cause the application of the brakes on the rear cars, if the rear valve of any car is closed, or on the forward cars, if the forward valve is closed. This provides a safeguard against the accidental or malicious closing of a valve without warning to the trainmen because the engineer cannot release the brakes which have been applied by this means without re-opening the valve and restoring the pressure in the entire trainline.

In the modification shown in Figs. 5, 6, and 8 there is a turnplug F' having a main transverse passage K' a by-pass L' and an upper by-pass M, the latter leading to an upper co-axial chamber N in which a valve O is mounted for independent manual operation by means of a handle P having a locking pin Q. Suitable pipes, not shown, connect the passage in the valve O with a suitable signal in the engineer's cab.

In the modification shown in Fig. 5, fastening means for my main valve serve to hold it against accidental closing while the train is in motion. This means consists of a valve handle R having an integral downwardly projecting lug S adapted to engage a suitable stop T on the valve casing which makes it necessary to lift the handle R until the lug S clears the stop T. The handle R is enlarged at its free end to form a counterweight, and is mounted for limited rocking on the turnplug to which the handle is fastened by a pin U. To aid the counterweight in fastening this valve, the handle R has an integral annular extension V against which a compression pin W presses a rivet-shaped bearing pin X.

The handle P carries a downwardly projecting lug P' which enters a suitable depression P² when in position for locking with the aid of a compression spring encircling the valve O.

To safeguard against the closing of the vent holes, the passages J² and J³, Figs. 5 and 7 respectively, are designed to give insufficient support for foreign matter when the closing of my valve applies the full train line pressure through my by-pass L'.

The form shown in Fig. 5 is particularly useful on locomotives, and the valve O should be closed whenever its locomotive is running "light" and when no rolling stock is coupled to the end which carries this valve.

My invention may be readily applied to standard M. B. C. equipment, and if desired, without even sending the cars and locomotives to the repair shop. It safeguards against train wrecks such as have often followed the accidental, or malicious, closing of the present type of valves, because it gives immediate warning to the engineer and before an emergency occurs which requires a sudden stop to avoid a serious wreck.

The form illustrated in Fig. 5 is adapted for giving immediate notice to the engineer whenever the steam supply valve is closed, and as a consequence no steam is being supplied to the heating pipes of the cars.

The applicant estimates that in the switching of railway cars there are from two thousand to three thousand emergency applications of the air brakes to one emergency application in road service. Such frequent emergency applications cause cumulative damage to the air brake equipment, including the brake rods, pivots and pistons, and as a result the equipment must be frequently repaired to be maintained in the most efficient condition.

The application's invention eliminates these switching emergency applications of the brakes and the delays at stations due to the present methods whenever a car is cut off or locomotives are changed.

With the applicant's method and apparatus, the fluid pressure is maintained at all times during the entire trip of each car, regardless of the number of switching movements required, in the air brake, water raising and steam heating systems of each, and the closing of any air line car end valve between the extreme ends of the train gives immediate warning and causes the train to be stopped automatically. The invention safeguards the trainmen against injury when uncoupling the hose. Operating costs are reduced by the saving of coal corresponding to the saving in steam and compressed air, and the cost, including time, of the excessive wear and tear of the equipment, which are due to the present methods of operation.

What I claim is:

1. In a trainpipe valve, the combination with a main turnplug provided with a transverse passage, a by-pass having an inlet opening between the opposite ends of said transverse passage an outlet through the base and

a second by-pass having an inlet opening on the opposite side of said plug, of a manually operated valve for said second by-pass mounted in said turnplug and means yieldingly resisting the turning of said second valve.

2. In a trainpipe valve, the combination with a turnplug provided with a transverse passage a by-pass between opposite ends of said passage adapted to open communication with the outside air and a second by-pass adapted to open communication with signaling means, of a turnplug for said second by-pass having yielding means for holding it against accidental movement, and a screw cap below said main turnplug provided with a self cleaning passage.

In testimony whereof I hereunto affix my signature.

FRANK J. GILROY.
